UNITED STATES PATENT OFFICE.

EDWIN R. GILL, OF YONKERS, NEW YORK, ASSIGNOR, BY MESNE ASSIGNMENTS, TO
HALL SWITCH & SIGNAL COMPANY, A CORPORATION OF MAINE.

AUTOMATIC SIGNAL-OPERATOR.

1,150,110.

Specification of Letters Patent. Patented Aug. 17, 1915.

Application filed August 4, 1909, Serial No. 511,259. Renewed August 24, 1914. Serial No. 858,348.

To all whom it may concern:

Be it known that I, EDWIN R. GILL, a citizen of the United States, residing in the city of Yonkers, county of Westchester, and State of New York, have invented a certain new and useful Improvement in Automatic Signal-Operators, of which the following is a specification.

The present invention has particular relation to automatic means for operating high speed selective signals for telephones, telegraphs and the like, and it may be used wherever a succession of long and short electrical impulses is to be produced under circumstances permitting permutation of the order of such impulses.

Many devices have been hitherto contrived whereby a number of signals at different points may be selectively operated over a single wire without interference among themselves, and among these an entire class is recognized wherein a movable contact piece is impelled forward rapidly step by step, the mechanism being so arranged that pauses may be produced after any one step forward, and so that each pause will cause a signal to operate at only one station. By pausing after the appropriate forward step, the operator is able to select whichever station he pleases and to call that station without disturbing any other upon the line. For convenience I shall refer herein to selective signaling means of this description as "high speed" signals.

My present invention is not concerned with the particular construction of any high speed selective signal and I have not illustrated such a signal herein, but its object is to supply means whereby merely depressing appropriate buttons and starting an automatic circuit breaker will produce a succession of electric impulses on a main line including pauses so ordered as to cause those stations corresponding to the buttons depressed to be called, and no others. It is to be understood, however, that my devices may be put to other than the above uses without departing from the scope of my invention.

The present invention relates particularly to certain modifications and improvements in the apparatus described in my pending application, Serial No. 458,204, filed October 17th, 1908, now Patent Number 1,024,444, patented Apr. 23, 1912, wherein certain broader claims are made.

A preferred embodiment of this invention is illustrated in the accompanying drawings wherein—

Figure 1 is a front elevation of a combined keyboard and auxiliary clockwork, a portion of the front being removed, Fig. 2 is a vertical section of the same on the plane 2—2 in Fig. 1, Fig. 3 is a perspective view of the escapement and the coöperating armature of the arrester, Fig. 4 is a section of the keyboard and switches, taken on the plane x—x in Fig. 2, Fig. 5 is a view of the preferred freeing device, Fig. 6 is an end elevation of the same, Fig. 7 is a partial elevation of the same viewed oppositely to Fig. 5, Figs. 8 and 9 are details of the freeing device shown on a large scale, and Fig. 10 is a diagram of circuits of an entire apparatus.

In my former application above mentioned there is described a combination of the following principal elements: First: An automatic switch normally producing a succession of impulses in rapid succession on the main line, called an automatic sender. Second: Means for producing a pause in the sender in any desired position corresponding to production of an electric impulse, called the automatic arrester. Third: Means for selecting and determining the particular positions of the sender at which the arrester becomes operative, called the pause controller. Fourth: Automatic means whereby after an appropriately timed pause, the action of the arrester is discontinued and the sender is freed, called the freeing device.

My present invention comprises some or all of these elements, but includes a certain improvement in the third element or "pause controller", whereby the same can be built up of sections which can be simply assembled side by side in such numbers as may be desirable in any given installation, the automatic restoration of all the keys in each section being accomplished by a single agency for each section.

The invention also comprises certain changes in the other elements of the whole apparatus, whereby they are made practical in combination with the improved form of apparatus above named.

Referring first to Fig. 10, the main line upon which are connected all of the selective signals or other devices intended to receive the impulses produced is shown at 10, and

the local relay controlling the main circuit at 11. In the exemplifying form shown in the accompanying drawings, the circuit closer used as an automatic sender comprises 5 an insulated contact piece 12 and a movable contact piece 13. This latter, as shown, comprises a spring terminal which is controlled by clockwork, to the frame of which it is electrically connected. These two contacts are so connected to the battery 14 and the relay 11 as to close the main line circuit whenever brought together.

The operating clockwork comprises a main spring 15, which tends always to turn the 15 main shaft 16 in the direction indicated by the arrow on the gear wheel 17 (see Fig. 1). This wheel is fast on the shaft 16, and, through a train of gears shown in dotted lines, it impels a coarsely toothed wheel 18. 20 The spring terminal 13 carries a finger 19, so placed with relation to the wheel 18 that, as the latter turns with the arrow shown upon it in Fig. 1, said finger, and the terminal 13 with it, are raised by each tooth of the wheel 18 in succession, thus closing and opening the relay circuit at 12 at regular intervals. For the purposes of my complete 25 system, the wheel 18 should have two more teeth than the total number of selective signals for which the complete apparatus is designed.

The motion of the clockwork is controlled in a well known manner by an escapement 20 comprising an extension 21 for a purpose described hereinafter.

The main shaft 16 can be turned by a handle 22 and carries with it an arc-shaped stop arm 23 against which a stop pin 24 on the wheel 18 normally bears. In operating the 40 device, the handle 22 is turned oppositely to the arrow in Fig. 1, until the stop arm strikes the pin 25. This frees the wheel 18, which turns with the arrow marked on it in Fig. 1, and the movements of the various 45 shafts are so related that, when the wheel 18 has made one revolution, the pin 24 again strikes the stop arm and stops the clock-work.

The frame of the clockwork is fixed to a 50 metal strip 26 which connects, by the flat terminal 27 and wire 28, with the battery 14. The insulated terminal or contact piece 12 is connected by wires 29, 30 to one side of the relay 11.

55 The mechanism and connections thus far described suffice for producing a rapid succession of electrical impulses on the main line. In order to make these useful in selectively operating the type of signals heretofore mentioned, however, it is necessary to provide means whereby a long impulse is produced at the proper moment or moments for calling the desired station or stations. The automatic arrester is used for this purpose.

In Figs. 1 and 3, an electro-magnet 31 is provided which controls a pivoted armature 32, normally kept away from the magnet pole by the springs 33. This armature carries a finger 34, so placed that, when the magnet is energized, the tip of said finger catches the tip of the extension 21 of the escapement and stops the clockwork. The means whereby the action of the arrester is appropriately timed is termed the pause controller.

In the improved form shown herein, the pause controller comprises a keyboard made up of sectional units, two of which are illustrated in Figs. 1, 2 and 4. These two units 80 comprise nine selective keys and one "set" button as indicated clearly in Fig. 1. It should be here explained that ordinarily only one "set" button need be used, whatever the number of sectional units employed for 85 a group of stations to be called.

As shown in Figs. 2 and 4 each self supporting unit is furnished with its own separate framework 36, which supports a row of tilting keys 37, mounted each on the end of a separate revoluble shaft 38. Each shaft is arranged to close a separate spring switch, preferably by means of a thimble 39 of insulating material, against one flat face of which bears one of a pair of contact springs 40, 41. These springs are omitted from Fig. 4.

It will be seen that the shape of the thimbles 39 is such that rotation of a shaft 38 will cause a corresponding spring contact 40 100 to move toward its appropriate spring 41 until contact is made, closing a circuit for a purpose described hereinafter.

The key marked "set" is shown at the bottom of Fig. 2, and it will be seen that the thimble 39 on this key, instead of closing a circuit when turned, as described above, acts, on the contrary, to open a circuit by pressing the contact spring 42 away from the spring 43. All the springs 40 in each 105 sectional group are electrically united as shown in Fig. 2, and, in that group which includes a "set" key, the spring 43 is electrically connected to all the springs 40. As shown in Fig. 10, a common wire 44, unites 110 all the springs 40 in all of the sectional groups or units which are combined in any station.

As will be seen by inspection of the drawings, all the springs 40, pressing upon the thimbles 39 when tilted, tend to return all the keys to the normal position shown in the drawings, and consequently means must be provided for holding the keys in closed circuit position and automatically permitting return of said keys to normal at the proper times. For this purpose each shaft 38 carries an armature 45 which tips toward and against the face of an electro-magnet 46 which extends past all the shafts 38 in each 115 120 125 130

group or unit. Each magnet 46 is provided with a coil of fine wire 47 the ends of which terminate in the binding posts 48, 49. The posts 49 in any number of combined or associated units are all electrically united by appropriate connections 50 (see Fig. 10).

The second binding post 48 in each unit is connected by wire 51 with a contact spring 52 near the top of the unit, and a second spring 53 is adapted to make and break contact with the spring 52 at the proper time for energizing and deenergizing the magnet 46, whereby the armatures 45 are all either held or released together.

For the purpose of operating the switch 52, 53, means are supplied which are operative whether one or more of the keys in any one unit or group are tilted. In the preferred form shown I use a sliding rod 54 extending past all the shafts 38 and carrying an insulated arm 55 upon which bears the spring 53, so that when the rod 54 is lifted contact will be made between the springs 52, 53. The rod 54 also carries lifting arms 56 which project over the thimbles 39 and lie normally upon the upper flat surfaces. Owing to this construction, the turning of any one thimble 39 by tilting a key 37 raises the rod 54 and closes the contact at 52, 53. The weight of the rod 54 and the resiliency of the spring 53 act with the tendencies of the springs 40 and 42 to return the keys to normal.

The line setting means governed by the key marked "set" are not indispensable to my invention but are preferably employed, and, when used, the springs 40 in all the combined units are normally connected, through the springs 42, 43, to the movable member of the selecting switch which forms part of the pause controller, in a manner and for a purpose described hereinafter.

The shaft 57 of the toothed wheel 18 preferably carries the movable member of the selecting switch. This is a spring arm 58 arranged so that its tip passes into the spring-jaw contacts 59, 60 placed in a circle around the shaft 57 as a center; and the arm 58 is so placed that it touches said contacts 59 at the same time that a corresponding tooth of the wheel 18 is acting to close the relay circuit at 12, 13. There is one contact 59 connected electrically to each contact spring 41 in the combined units, and in addition one contact 60 connected to all the springs 40 by the wires 61 and 44 (see Fig. 10). The wheel 18 has one tooth corresponding to each spring-jaw contact 59 and one for the contact 60.

The arm 58 normally bears at its opposite end upon a metal ring 62, save when the notch 63 in said ring is reached. The ring 62 is connected by the wire 64 to the spring contacts 53 in all the associated units.

As shown in Fig. 10, the magnet 31 of the

automatic arrester has coils whose ends are connected to binding posts 65, 66, which in turn are connected by wires 67, 68, to the spring contact 43 opposite the "set" key on the one hand, and, on the other hand to the binding post 69 of the "freeing device" now to be described.

In order that the action of the automatic arrester may be discontinued after a proper time interval, thus limiting the duration of pauses produced thereby, a freeing device must be employed, and for this purpose I prefer to use the apparatus shown in Figs. 5 to 9 and in diagram in Fig. 10.

Here the casing 70 incloses a framework 71 supporting a horizontal shaft 72 carrying a ratchet wheel 73 which is normally impelled in the direction of the arrow in Fig. 7 by the spiral spring 74. The electromagnet 75 (omitted from Fig. 6) acts through the armature 76, bent spring 77 and wire 78 to operate an impelling lever 79. An impelling pawl 80 is pivoted to the end of the lever 79 and is so placed that, whenever energization of the magnet 75 permits the lever 79 to move downward, said pawl will move the ratchet wheel 73 one tooth forward. When the impelling pawl 80 rises, the retaining pawl 81 on the pivoted arm 82 acts on the teeth of the ratchet 73 to prevent return to normal under the influence of the spring 58.

For purposes described hereinafter, the lever 82 is carried on a shaft 83 capable of moving longitudinally upon the long journals shown in Fig. 6, thus permitting the pawl 81 to be disengaged from the wheel 73 by lateral movement. The inclination of the shaft 83 facilitates return of the pawl over the wheel as hereinafter described, and also tends to keep the pawl always over the wheel when it is intended to be there.

For the purposes described hereinafter it is desirable that the action of the wheel 73 and its driving parts should be substantially as follows: When the wheel is at normal and before any call is begun, any rapid impulses should produce only a back and forth motion through the space of one tooth. When a call is to be begun, a pause during an impulse (the magnet 75 being energized) should prepare the wheel for action. Thereafter every impulse, whether including a pause or not, should cause the wheel to move forward one step without backward movement, and this should continue until as many steps have been taken as there are selective calls in the particular system to be operated, after which the wheel should return to its original or normal position, in readiness for a new complete operation.

Fig. 8 shows the normal position of the wheel 73 and lever 82. In this position the lever 82 is supported in an elevated position with the pawl 81 out of engagement, due to

the fact that the catch 84 rests on the hook 85 which is fixed to the revoluble shaft 86 (see Fig. 6). This engagement between the catch 84 and the hook 85 is permitted by the 5 tail piece 86' of the hook bearing on the flattened part of the hub 87, fixed to the shaft 72. The movement of the wheel 73 the distance of one tooth does not cause sufficient movement of the hook 85 to liberate the lever 82 and drop the pawl 81 upon the wheel, and therefore any number of quick movements of the impelling pawl 80 merely produce quick back and forth movement of the wheel 73.

15 In order to cause the wheel 73 to progress through its whole intended course, means are provided whereby a pause of sufficient duration occurring while the pawl 80 is depressed causes the pawl 81 to be dropped 20 upon the wheel into position to hold the same during upward movements of the impelling pawl 80. For this purpose I prefer to employ the following means: Upon a shaft 88 there is fixed a lever 89, to the outer 25 extremity of which is pivoted a framework 90 carrying a pair of inertia wheels 91 fixed to a short shaft 92 resting upon the inclined track 93. These wheels 91 are held near the upper end of the track 93 by the arm 94 30 fixed on the shaft 95, to which is also fixed the lever 79 which carries the impelling pawl 81. Thus each time the impelling pawl 81 is depressed the wheels 91 begin to roll slowly down the track 93, and whenever the 35 pawl 80 rises the arm 94 causes the wheels to slide quickly back up the track 93. If the impelling pawl 80 be depressed long enough, the wheels 91 will roll down far enough to permit the framework 90 to hit the lever 96. 40 This lever is fixed to the revoluble shaft 86 to which the hook 85 is fixed. This action pushes the hook 85 away from under the catch 84, thus releasing the pawl 81, and permitting it to fall upon the wheel 73. After this, as 45 the wheel progresses step by step under the influence of the impelling pawl 80, the catch 84 does not at any time rise high enough to rest upon the hook 85, which, moreover, is held out of engaging position by the rounded 50 portion of the hub 87. It follows therefore that, whether the forward impulses follow each other quickly or with intermediate pauses, the wheel 73 will move forward until the inclined tooth 97 comes in contact 55 with the pawl 81. The inclined face of said tooth will cause the lever 82 and pawl 81 to move laterally so as to release the wheel. The spring 74 (see Fig. 6) at once returns the wheel to normal, at the end of which return movement, the lifting catch 98 on the wheel 73, acting upon the inclined forward face of the lever 82, raises the catch 84 onto the hook 85, and the inclined pin 99 on the wheel causes return lateral movement where- 60 by the pawl 81 is restored to the plane of

the wheel 73. The pin 99 may be used alone in some cases, but, where a wheel with many small teeth is used, I have found it advisable to use the construction shown. It will thus be seen that, by beginning with a long impulse the wheel 73 may be progressed any predetermined number of teeth, pauses being made at any desired intervals. The object of the entire "freeing device" is to cause the opening of a normally closed circuit at 75 intervals selected at will by making pauses or long impulses at proper intervals. For this purpose a fixed contact piece 100 is connected to the frame of the machine, which is itself connected to the binding post 101 (see 80 Fig. 10). A movable spring contact 102 is fixed to an insulating piece 103 on the shaft 88 which turns with the lever 89. The tension of the spring 102 is such that it does not actually leave the contact 100 until the 85 wheels 91 have rolled down the track 93 a distance corresponding to a prearranged interval of pause during depression of the impelling pawl 80. The movable spring terminal 102 is connected by a fine flexible connection 104 to the insulated bar 105, connected by wire 106 to the binding post 69 (see Figs. 6 and 10).

In Figs. 8 and 9 are shown certain minor details of improvement. One of these is the 95 guide piece 107, provided with two upwardly extending arms, between which plays the lower or working end of the impelling lever 80. These arms serve to control the movements of the lever with relation to the teeth of the wheel 73, and their position can be accurately adjusted in any given instrument by means of the screw 108, upon which the guide piece is pivoted. The pawl 80 is pivoted to the lever 79 as shown 100 in Fig. 9, and is provided with an arm 109 against which bears the spring 110. This spring keeps the lower end of the pawl normally in contact with the inner arm of the guide piece 107, thus directing the pawl 80 105 exactly into each successive tooth on the wheel 73. I have found these details of construction particularly useful where a wheel 73 with many fine teeth is used.

In operating the system so far described 115 in connection with selective stations signals of the type above referred to, any one or all of the stations on the line may be called successively by one operation.

Supposing it were desired to call stations 1 and 4, for instance, and to leave all other stations undisturbed. The operator will first push forward the two keys numbered 1 and 4 and no others and then turn the handle 22 as far as it will go to the right and release it. The main spring 52 revolves the shaft 57, the arm 58 and the toothed wheel 18. During movement of the clockwork, the circuit-closing positions of the keys 1 and 4 are preserved by the armature 45 being attract- 120 125 130

ed by the magnet belonging to the group to which these keys belong. The circuit of this magnet is closed by upward movement of the sliding rod 54, whereby contact is made between springs 52 and 53 and current passes from battery 111, to binding post 49 belonging to the proper group or unit, through coils of the magnet 46, binding post 48, proper wire 51, contacts 52, 53, wire 64, ring 62, arm 58, wire 28 and wire 112 to battery. The first operation takes place when the arm 58 touches the contact piece 60 and the first tooth on wheel 18 lifts the finger 19 so as to produce the first contact at 12, 13. At the moment these contacts occur current passes from battery 14 by wire 28, machine frame, contacts 13, 12, wire 29, to magnet 75 in the "freeing device", and back to battery 14. The impelling pawl 80 is thus depressed, and the depression is prolonged so as to produce action of the retarded mechanism which trips the hook 85, by the following means. Contact between the arm 58 and the spring-jaw 60 closes a circuit starting from battery 113, by wires 112 and 28, to shaft 57 and arm 58, contact 60, wire 61, wire 44 and wires connecting all the springs 40, by springs 43, 42 at the "set" key, wire 67, post 65, magnet 31, post 66, wire 68, post 69 on the "freeing device", contacts 102, 100, post 101 and back to battery 113. The magnet 31, being thus energized, acts by armature 32 and finger 34 to arrest the clockwork, so that a prolonged contact is produced at 12, 13, thus permitting the wheels 91 in the "freeing device" to roll down the track 93 far enough to trip the hook 85 so as to prepare the "freeing device" for progressive movement of the wheel 73. At the same time, or a little later, contact is broken at 100 and 102, thus de-energizing magnet 31, and permitting the clockwork to continue its forward movement. In the meantime, a branch circuit is closed from battery 14, by wire 28, machine frame, contacts 13, 12, wire 29, wire 30, relay 11, and back to battery 14. This closes the main line circuit to all the selective calling instruments, and the interval being a prolonged one, all of said instruments are prepared in a well known manner for forward movement and appropriate operation. Further movement of the clockwork now brings the arm 58 into contact with the first spring-jaw 59, and current flows from battery 14, by wire 28, arm 58, contact 59, wire 114, springs 41, 40, of key No. 1, by wires connecting all springs 40 to springs 43 and 42, by wire 67, to magnet 31 as before and back to battery. At the same time prolonged action of the "freeing device" magnet 75 takes place as before due to circuit through 13 and 12 and the wheel 73 moves forward another tooth. A long impulse is again sent over the line, and that se-

lective instrument which is arranged to operate on prolongation of the first impulse produces a signal. The clockwork being released by action of the freeing device as before, contact occurs successively at the second and third spring-jaws 59. These are connected as shown to springs 41 at keys 2 and 3, but, as said keys have not been tilted, the magnet 31 is not energized and the only result is progress forward by one more tooth of the wheel 73 in the "freeing device" and of the corresponding wheels in all the selective instruments along the line. When the arm 58 reaches the fourth contact 59, the arrester magnet 31 comes again into play owing to the position of key No. 4, and the operation above described for number 1 is repeated. The entire revolution of the arm 58 is completed, and, just as the arm 58 reaches the last contact 59, the opposite end of said arm reaches the notch 63, whereby circuit is broken through all the magnets 46 which happen to be energized. This releases all the tilted keys, which at once return to normal, in preparation for another operation. The arm 58 then advances to the normal position shown, the same being in contact with the ring 62 preparatory to again using the entire apparatus. In this position the arm remains, the pin 24 having struck the arm 23.

It will be seen that the number of teeth on the wheel 73 in the actual "freeing device" shown is considerably greater than the number of contact points 59. In practice the number of teeth counting from normal position of the wheel 73 around to the beveled tooth 97 should be equal in number to the contacts 59, but a fewer number of the latter contacts have been shown in Fig. 105 as it would unduly complicate the drawing to show therein more than two groups or sectional units.

The use of the "set" key is to bring all selective instruments on the main line with certainty to normal or initial position when there is reason to suspect that one or more of them have been accidentally displaced. This may be done without operating any signal as follows:—

The "set" key is tilted, being held by its appropriate magnet 46 as before described. The handle 22 is then turned or released as before. As the arm 58 reaches each spring-jaw in its path, there is no action of the 120 arrester magnet 31, because its circuit is broken at 42, 43. The closures of circuit produced at 12, 13 are therefore all quick ones, and, in case any selective instruments on the line are accidentally advanced at the 125 commencement of the operation being described, such instruments are carried to the end of their allotted movement where they automatically return to normal. Any further impulses reaching such instruments 130

after return to normal will not cause further progression in them, owing to the fact that a prolonged or retarded initial impulse is necessary to start them.

5 Just before the end of the operation above last described the arm 58 again reaches the notch 63, and the "set" key is released by de-energizing its magnet, as above described in the case of normal operation.

10 Many changes may be made in constructions above described without departing from my invention and I do not limit myself to details herein shown and described.

Having described my invention what I 15 claim as new and desire to secure by Letters Patent is:

1. A device of the class described comprising in combination an automatic sender adapted to normally produce a succession of 20 rapid electric impulses, an automatic arrester adapted to interrupt the action of said sender, a group of keys adapted to control the operation of said arrester, and an electro-magnet associated with said group and 25 adapted to hold any plurality of said keys in a predetermined position to which they may be successively moved, substantially as described.

2. A device of the class described comprising in combination an automatic sender adapted to normally produce a succession of rapid electric impulses, an automatic arrester adapted to interrupt the action of said sender, a number of groups of keys 30 adapted to control the operation of said arrester, an electro-magnet associated with each of said groups and each adapted to hold in a predetermined position to which they may be successively moved any 35 plurality of its own group, and an electric circuit for controlling said magnets and having a separate branch including the coils of each magnet, substantially as described.

3. A device of the class described comprising in combination an automatic sender adapted to normally produce a succession of rapid electric impulses, an automatic arrester adapted to interrupt the action of said sender, a freeing device adapted to 40 limit action of the arrester, circuits connecting said devices, a group of keys connected in said circuits for controlling said devices and an electro-magnet associated with said group and adapted to hold any one of said 45 keys in a predetermined position, substantially as described.

4. A device of the class described comprising in combination an automatic sender adapted to normally produce a succession of rapid electric impulses, an automatic arrester adapted to interrupt the action of said sender, a group of keys adapted to control the operation of said arrester, an electro-magnet associated with said group and 55 adapted to hold any one of said keys in

a predetermined position, a circuit for said magnet, and an automatic circuit breaker in said circuit adapted to move with said sender, substantially as described.

5. A device of the class described comprising in combination an automatic sender adapted to normally produce a succession of rapid electric impulses, an automatic arrester adapted to interrupt the action of said sender, a group of keys adapted to 70 control the operation of said arrester, an electro-magnet associated with said group and adapted to hold any one of said keys in a predetermined position, a circuit for said magnet, a rotary arm adapted to move with said sender and a plate along which said arm moves when rotating, said arm and plate both being in said magnet circuit, and said plate being shaped so that said arm breaks contact with it at one point, substantially as described.

6. A device of the class described comprising in combination an automatic sender of rapidly recurring electrical impulses, an automatic arrester therefor, a group of keys and corresponding circuit closers, an electro-magnet for holding said keys, a series of contact points electrically connected to said circuit-closers, a contact plate electrically connected to the coils of said electro-magnet, 95 and a contact arm adapted to move with said sender and placed so that one of its ends sweeps over said series of contact points and its opposite end sweeps along said contact plate, substantially as described.

7. A device of the class described comprising in combination a toothed wheel intended to be advanced a predetermined distance, means for returning the same to normal, a retaining pawl for said wheel, a pivoted lever therefor mounted so as to be movable laterally, means on the wheel adapted to move said lever laterally, means on the wheel adapted to act upon said lever to raise 105 said pawl and lever when the wheel returns to normal, and a second means on said wheel adapted to move said lever and pawl laterally toward said wheel, when the latter returns to normal, substantially as described. 110

8. A device of the class described comprising in combination a toothed wheel intended to be advanced a predetermined distance, means for returning the same to normal, a retaining pawl for said wheel, a pivoted lever carrying said pawl, a hook adapted to engage said lever, and means moved directly by said wheel for controlling the position of said hook, substantially as described. 120

9. A device of the class described comprising in combination a toothed wheel intended to be advanced a predetermined distance, means for returning the same to normal, a retaining pawl for said wheel, a piv- 125

- oted lever carrying said pawl, a hook adapted to engage said lever and having a tail piece extending past the shaft of said wheel and a flattened hub fixed to said wheel and 5 so placed as to control the engagement of said hook with said lever on rotation of said wheel, substantially as described.
10. A device of the kind described comprising in combination an automatic sender adapted to normally produce a succession of 10 rapid electric impulses, an automatic arrester adapted to control the operation of said sender, a group of movable keys adapted to control the operation of said arrester, 15 and a single means associated with said group and adapted to hold any plurality of said keys in a predetermined position to which they may have been successively moved.
20. 11. A device of the kind described, comprising in combination, an automatic sender adapted to normally produce a succession of rapid electric impulses, an automatic arrester adapted to control the operation of 25 said sender, a group of movable keys adapted to control the operation of said arrester, a single means associated with said group and adapted to hold any plurality of said keys in a predetermined position to which 30 they have been successively moved, and means for rendering said last named means operative, controlled by the movement of any key.
12. A device of the kind described comprising an automatic sender adapted to normally produce a succession of rapid electric impulses, an automatic arrester adapted to control the operation of said sender, a group of movable keys adapted to control the 35 operation of said arrester, and a single means associated with said group and adapted to hold any one or plurality of said keys in a predetermined position to which they may be successively moved.
40. 13. A device of the kind described, comprising in combination, an automatic sender adapted to normally produce a succession of rapid electric impulses, an automatic arrester adapted to control the operation of 45 said sender, a group of movable keys adapted to control the operation of said arrester, a single means associated with said group and adapted to hold any plurality of said keys in a predetermined position to which 50 they may be successively moved, and means for rendering said last named means operative, controlled by the movement of any key.
45. 14. In a device of the kind described, a plurality of switches, a key for each switch, 60 an electro-magnet for holding any plurality of said keys in a determined position to which they may be successively moved, a circuit for said magnet, and a means for controlling said circuit controlled by the movement of any one of said keys.
15. In a device of the kind described, a plurality of keys, an armature for each key, a magnet common to the armatures, a circuit including the magnet, and a switch for the magnet circuit adapted to be mechanically operated by said keys. 70
16. In a device of the kind described, a plurality of keys, an armature connected to each key, a magnet common to the armatures, a circuit including the magnet, a switch for the magnet circuit adapted to be mechanically operated by any one of said keys, and an independent circuit controlled by each of said keys. 75
17. In a device of the kind described, a plurality of keys, an armature connected to each key, a magnet common to the armatures, a circuit including the magnet, a switch for the magnet circuit adapted to be mechanically operated by any one of said keys, and automatically operative means for breaking the magnet circuit. 80
18. In a device of the kind described, a plurality of keys, an armature connected to each key, a magnet common to the armatures, a circuit including the magnet, a switch for the magnet circuit adapted to be mechanically operated by any one of said keys, and manually operated means for breaking the magnet circuit. 85
19. In a device of the kind described, a plurality of keys, an armature connected to each key, a magnet common to the armatures, a circuit including the magnet, a switch for the magnet circuit adapted to be mechanically operated by any one of said keys, automatically operative means for breaking the magnet circuit, and manually operative means for breaking the magnet circuit. 90
20. In a device of the kind described, an automatic sender of electrical impulses, an automatic arrester therefor, a group of keys and corresponding circuit closers, an electro-magnet for holding said keys, a series of contact points electrically connected to said circuit closers, a contact plate electrically connected to the coils of said electro-magnet, and having a cut-out portion, and a contact arm adapted to move with said sender, and placed so that one of its ends sweeps over said series of contact points and its opposite end sweeps along said contact plate, excepting at the cut-out portion, substantially as described. 100
21. In a device of the kind described, a plurality of keys, armatures moved by the keys respectively, a magnet common to the armatures, a circuit including the magnet, a switch for the magnet circuit movable upon movement of any key, and a spring circuit closer controlled by each key respectively, said springs urging said several keys to movement. 110
22. In a device of the kind described, an 120
- 125
- 130

automatic sender adapted to normally produce a succession of electrical impulses, an automatic arrester adapted to interrupt the action of said sender, a group of keys adapted to control the operation of said arrester, a spring circuit closer controlled by each key respectively, said springs urging their several keys to movement, an electro-magnet associated with said group of keys, and 5 adapted to hold any one of said keys in a predetermined position, a circuit for said magnet including a movable contact, and a movable member operatively related to said contact and movable by any one of said 10 keys.

23. A device of the class described, comprising in combination an automatic sender adapted to normally produce a succession of rapid electric impulses, an automatic arrester adapted to interrupt the action of said sender, a number of groups of keys 20 adapted to control the operation of said arrester, an electro-magnet associated with each of said groups and each adapted to hold in a predetermined position to which they may be successively moved any plurality of keys of its own group, an electric circuit for controlling said magnet and having a separate branch including the coils of 25 each magnet, substantially as described, and automatically operative means for controlling said circuit.

24. A device of the class described, comprising in combination an automatic sender 35 adapted to normally produce a succession of rapid electric impulses, an automatic arrester adapted to interrupt the action of said sender, a number of groups of keys adapted to control the operation of said arrester, an electro-magnet associated with each of said groups and each adapted to hold in a predetermined position to which they may be successively moved any plurality of keys of its own group, an electric 40 circuit for controlling said magnet and having a separate branch including the coils of 45 each magnet, substantially as described, and automatically operative means for controlling said circuit.

each magnet, substantially as described, and manually operated means for controlling said circuit.

25. A device of the class described, comprising in combination an automatic sender adapted to normally produce a succession of rapid electric impulses, an automatic arrester adapted to interrupt the action of said sender, a number of groups of keys 50 adapted to control the operation of said arrester, an electro-magnet associated with each of said groups and each adapted to hold in a predetermined position to which they may be successively moved any plurality of keys of its own group, an electric circuit for controlling said magnet and having a separate branch including the coils of 55 each magnet, substantially as described, automatically operative means for controlling said circuit, and manually operated means for controlling said circuit.

26. In a device of the kind described, a plurality of keys, an armature for each key, a rod extending past each of said keys and 70 having a plurality of fingers, one for engagement with each of said keys, a magnet common to said armatures, and a circuit for said magnet including a movable contact operatively related to said rod.

27. In a device of the kind described, a plurality of pivoted keys having portions of oblong cross-section, an armature attached to each key, a slideable rod extending past each of said keys and having a plurality of 80 fingers, one for engagement with the aforesaid portion of each key, a magnet common to said armatures, and a circuit for said magnet including a movable contact operatively related to said rod.

In witness whereof I affix my signature in the presence of two witnesses.

EDWIN R. GILL.
